UNITED STATES PATENT OFFICE.

JOHN RANDOLPH FLETCHER, OF DAYTON, OHIO.

BED-WARMER.

1,383,197.

Specification of Letters Patent. Patented June 28, 1921.

Application filed January 16, 1920. Serial No. 351,746.

To all whom it may concern:

Be it known that I, JOHN RANDOLPH FLETCHER, a citizen of the United States, residing at Dayton, in the county of Montgomery and State of Ohio, have invented certain new and useful Improvements in Bed-Warmers, of which the following is a specification, reference being had therein to the accompanying drawing.

10 This invention relates to bed-warmers and has for its object to provide a simple, effective bed-warmer of an improved type which will be safe to use under all conditions, being low in first cost, practically indestructible and having little or no maintenance cost.

It is an object of the invention to provide a bed-warmer which cannot become overheated and thus cause danger of fire, and which will have no exposed heated parts 20 which might come in contact with and burn or cause discomfort to an occupant of the bed.

In the accompanying drawings, Figure 1 is an elevation of an ordinary electrical lamp 25 with lamp guard and covering fabric in section; and

Fig. 2 is a top plan view of the lamp and guard with the fabric thereon in section.

As shown in the drawings the improved 30 bed-warmer consists of an ordinary electrical extension cord 1, provided at one end with a plug 2, adapted to be inserted into any convenient and suitable socket to make the electrical connections. At the opposite 35 end the cord is provided with an electrical bulb or lamp 3, of suitable kilowatt capacity, the preferred size being a 15-kilowatt lamp. Other sizes of lamps of larger or smaller capacity may, of course, be substituted as 40 may be required or desired by the user.

No novelty is claimed relative to the extension lamp and connections, as the usual 45 form of electrical extension lamp is the preferred device for the purposes of the invention, the lamp being also provided, preferably, with the usual type of metal lamp guard 4, which serves to protect the bulb from accidental breakage, and also serves a further purpose in connection with the invention, which will presently be described.

The lamp cord as here shown may also be provided with a cut-out 5, in addition to the

usual cut-out 6 of the lamp to conveniently control the lamp to turn the current on or off without displacing the lamp.

55

The invention consists in covering the lamp and lamp guard with a porous or open-mesh fabric 7 of suitable material, such as cotton or wool flannels, which will readily conduct or permit the heat to pass therethrough, the cover being tied about the lamp guard in any suitable manner as shown for illustrative purposes at 8 and 9 to form a sack or complete cover.

60

In use the lamp cover will not materially affect the radiation of heat from the lamp, but will act to effectually cover all heated parts of the lamp so that the same cannot come in direct contact with the bedding or an occupant therein.

65

70

The invention has the advantages of

cheapness, simplicity, and great effectiveness and may be installed and used without

the services of a mechanic or electrician in

connection with any electrical wiring sys-

75 tem provided with the usual lamp sockets.

In electrical bed warmers of present well

known types the heating coils are made of

fine copper wires covered with asbestos.

When left to run at full heat, these warmers

80

become overheated, thus tending to melt

the wires and developing danger of fires.

This type of warmers are too delicate or

fragile and are frequently in need of re-

85

pairs, which adds to the cost of operation

and interferes with their use. These dis-

advantages are fully overcome in the im-

90

proved warmer of the present invention,

which can be procured and operated at lower

cost and without danger of accident.

95

While the invention is herein described as

a bed-warmer, it will be obvious that the

warmer may be used generally for many

household or sick-room uses in which hot

95

bottles or other warming devices or means

are commonly used.

Having thus fully described my invention,

what I claim as new and desire to secure

by Letters Patent, is:

100

In an electrical warmer, the combination of a lamp having a thumb switch and provided with a lamp guard of framework sufficiently open not to interfere seriously with the light from the lamp, and a non-metallic,

non-heat-absorbing fabric arranged about said guard and lamp but terminating short of the thumb switch to cover parts that become heated from said lamp, a cut out 5 whereby the lamp user may cut off the current at a distance without reaching for the lamp, the lamp guard having indentations

at both ends whereby cords may be passed around said fabric and hold it securely to the guard.

10

In testimony whereof, I affix my signature.

JOHN RANDOLPH FLETCHER.
